UNITED STATES PATENT OFFICE.

JOHN A. HANSON, OF HUNTERS, WASHINGTON.

RADIO APPARATUS.

Application filed September 9, 1924. Serial No. 736,726.

This invention pertains to apparatus for receiving forces to be used in connection with electric and radio appliances and has for its object to provide an apparatus that will operate in connection with a radio receiving set without ground connections. The apparatus comprises a construction in annular form embodying an insulated iron core with sectional windings of insulated wire with contacts for connection at the end of each winding. The apparatus functions by certain connections when used with a radio receiving set for receiving messages. The apparatus will be hereinafter particularly described, 15 illustrated in the accompanying drawings and pointed out in the appended claim.

In the drawing:

Fig. 1, is a view in side elevation of the device of my invention.

Fig. 2, is a central sectional view thereof.

Fig. 3, is an enlarged sectional view on line 3—3 of Fig. 1.

Fig. 4, is a diagrammatic view showing the device of my invention connected up in an aerial circuit.

Like characters of reference designate similar parts throughout the different figures of the drawing.

My invention consists of or comprises an apparatus to be used for electrical purposes, 30 and more particularly in the aerial circuit of a radio set, for improvement of radio reception.

I employ a metallic core of ring form and 35 which, as shown, consists of sections 11 and 12, of laminated formation, the ring core, as shown in Fig. 3, being circular in cross section. However, I do not wish to be limited to this precise construction, as it is only important that the core be of para magnetic metal and that it be of some type of endless form.

The invention involves two open circuit windings in superimposed relation with respect to each other and the core, and I will 45 designate one of said windings as the inner or aerial winding, and the other as the outer or receiver winding. I will also designate those terminals of the windings forming the beginning of the first turns or convolutions as "the starting terminals" and those terminals ending the last turns or convolutions as the "ending terminals."

Next referring specifically to Fig. 3, I dis-

pose a suitable insulating covering 13, about 55 the core. About this insulated core I dispose one layer 14, of the aerial winding, covering the same with insulation designated at 15, and onto the latter I dispose one additional layer of the aerial winding, as indicated at 60 16. Both layers consist of a single length of suitably insulated wire which is wound about the periphery of the insulated core in one direction. The starting terminal of this inner or aerial winding is indicated at 9, in 65 Fig. 2, such terminal being nearest the core, and terminal 9 is extended radially inwardly of the ring core and is connected with a contact 21. Contact 21, is adapted for connection with aerial 27, by wire 26, as shown in 70 Fig. 4. An ordinary aerial or an electric lighting circuit or system may be used as an aerial, if desired. The outer or ending terminal of the aerial winding, which is farthest from the core, is indicated at 8, and the 75 same is extended radially inwardly of the device and is connected with a contact 22, which may be used for testing and other purposes but which is not utilized when the device of my invention is functioning in a 80 service connection, as shown in Fig. 4.

I will next describe the outer or receiver winding and will refer to Fig. 3.

The inner winding is covered by insulation 17, about which I dispose the first layer 85 of the outer winding 18, the latter being covered by insulation 19. The last layer 20, of the outer winding is disposed about the insulation 19, and this outer winding is 90 formed of a single length of insulated wire which is wound in the same direction as the inner winding. Of course, it is not material in which direction the convolutions are wound, just so that both windings are wound in the same direction. I have designated 95 the starting terminal of the outer winding, which is that terminal nearest the core, at 7, the same being extended radially inwardly and being connected with a contact 23, which is adapted for connection with the receiver set terminal 29, by wire 28, as shown in Fig. 4. The ending terminal of the outer winding is indicated at 6, and the same is shown connected with a contact 24, which like contact 22, is used for testing and other purposes but 100 which is not connected up when the device is in service, as shown in Fig. 4.

It will thus be clear, as before stated, the

inner and outer windings are open circuit windings, and that the wave impulses travel radially outwardly of the device from the inner winding. From Fig. 2, it will be clear that the convolutions of the inner and outer windings are continued peripherally about the center of cross section of the core until the entire circumference of the core is built up, as shown, the same being generally indicated at 10. A suitable outer covering of insulating material 25, is employed as shown.

10 I will next describe the theory of operation to the best of my knowledge.

15 Alternations pass from the aerial into the inner or aerial winding, setting up a field, and from this winding the alternations are induced into the outer or receiver winding. The presence of an iron core with two windings of wire, causes a large inductive effect, while the open windings cause the 20 device to function as a condenser. Now by tuning the radio set, it is possible to so change the value of the inductance or capacity of the circuit, that one balances the other, and the current has its least opposition, and 25 is therefore at its maximum value for a given frequency. This state of balanced inductance and capacitance is called resonance.

30 A station broadcasting at resonant frequency will be received, but all other stations above or below this frequency will not be received because the reactance of the circuit will be too large. The sustained oscillations at resonant frequency encounter an 35 ideal path, due to the combined electro-magnetic and condensance effect under which the aerial and its earth relations are held, while oscillations of no definite wave length caused by atmospheric conditions, artificial 40 electrical disturbances, etc., encounter a large reactance, and the only part of these strays of the same wave length that do enter, are of so small a value that the reception 45 is not disturbed and thus static is greatly minimized and sometimes entirely eliminated.

50 Due to the novel association of the open windings with the metal core, and the manner of connecting the windings with the aerial and receiver, the circuit is held under a high electro-magnetic effect, with the 55 electrical inertia high, and the current received is strengthened and held as though passing through a metallic path, hence fading of the voice or music is very rare, and a radio set will function with keener selectivity. Thus, fading in this respect is so minimized that it is practically eliminated.

60 This selectivity is clearly shown by the fact that more than one radio receiver can be worked from one and the same aerial, receiving either the same or different broadcasting stations without one receiver interfering with the reception of the other, or one receiver may be connected to the outside 65 aerial, while the other receiver is connected

to a light circuit, as an aerial, receiving the 70 same or different broadcasting stations at one and the same time without mutual interference.

75 Thus it will be seen that the device of my invention causes the presence of a greater inductance and capacity reactance in the circuit. When the inductance or capacity in the circuit is varied in tuning, resonance occurs for a given frequency and there is an 80 increase of current in the aerial circuit with respect to the current normally received by the aerial, hence, amplification of reception is obtained.

85 An important feature is that by means of an endless metallic core, and with the turns of both windings made wholly in one direction, I get a continuous and cumulative magnetic flux which increases induction and prevents flux interference.

90 It is also important to make the aerial and receiver connections with the windings at the starting terminals thereof because you thus connect the windings at points closest to the core and hence obtain a maximum effect of the windings on the core. Because the 95 windings are open, a condenser is formed, each winding acting as a condenser plate.

99 It is believed that the device of my invention will be fully understood from the foregoing description, and while I have herein shown one specific form of my invention, I do not wish to be limited thereto except for such limitations as the claims may import.

I claim:

1. In a device of the character described, 105 a ring shaped magnetic core, an inner or aerial winding wound about said core throughout the circumference thereof and composed of a plurality of layers, and an outer or receiver winding of a plurality of 110 layers wound about said inner winding, the turns of both windings being continuously convoluted in one and the same direction from end to end to prevent flux opposition, the ending terminals of said windings being 115 open and the starting terminals of the inner and outer windings being adapted for connection respectively with an aerial and a receiver.

2. In a device of the character described, 120 and endless magnetic core, an inner or aerial winding wound on said core throughout the circumference thereof, and an outer or receiver winding on said inner winding, the turns of both windings being convoluted in one and the same direction from 125 end to end to prevent opposition of flux, the ending terminals of said windings being open and the starting terminals of the inner and outer windings being adapted for connection respectively with an aerial and a receiver.

In testimony whereof, I affix signature.

JOHN A. HANSON.
